[57] CLAIM

The ornamental design for an air cushion with a finger pressure therapy like effect, as shown and described.

DESCRIPTION

FIG. 1 is a perspective view of an air cushion with a finger pressure therapy like effect showing my new design.

FIG. 2 is a front elevation.

FIG. 3 is a rear elevation.

FIG. 4 is a left side elevation, the right side being a mirror image thereof.

FIG. 5 is a top plan elevation; and,

FIG. 6 is a bottom plan elevation.
